UNITED STATES PATENT OFFICE.

JOSEPH MENCHEN, OF SUMMIT, NEW JERSEY, ASSIGNOR TO MADGE MENCHEN, OF NEW YORK, N. Y.

ALARM DEVICE.

Application filed January 21, 1922, Serial No. 530,755. Renewed April 6, 1925.

The invention relates to alarms for giving warning in event of unauthorized opening of a closure, more particularly a door or window of a house or apartment. An object is to provide a very simple and reliable cartridge-alarm mechanism, which can be easily and certainly put into and out of condition for action. A particular object is to provide a simple and compact 10 self-contained device of this nature adapted to be readily applied to a door or window.

In the accompanying drawings, forming a part hereof:

Fig. 1 is a face view of an alarm device 15 constituting a preferred embodiment of the invention, applied in this instance to the vertical face of a door-jamb at the inner side of the doorway, the device being shown in the position in which it does not interfere with the opening of the door;

Fig. 2 is a similar view, showing the interfering position;

Fig. 3 is a side view of the same device, applied to the top surface of the lower sash 25 of a window, the device being in non-interfering condition;

Fig. 4 is a view corresponding to Fig. 3 showing the interfering condition in this case;

Fig. 5 is a sectional plan view of the device, the plane of section being parallel with the base, and the firing-means being shown in the normal condition;

Fig. 6 is a similar view showing the firing- 30 means released and the cartridge exploded;

Fig. 7 is an end elevation corresponding to the condition of Fig. 5.

Fig. 8 is a cross-section through the device on the line 8—8 of Fig. 1;

Fig. 9 is a plan view of the base;

Fig. 10 is a cross-section on the line 10—10 of Fig. 1;

Fig. 11 is a fragmentary view looking at the under side of the firing-pin chamber at the region of the swivel;

Fig. 12 is an elevation showing how the device may be applied to the top of a window sash in conjunction with a fume or gas producer actuated by the flash of the cartridge, a similar combination being applicable also in case of doors or other closures;

Fig. 13 is an axial section through the cartridge chamber removed and empty; and

Fig. 14 is a fragmentary axial section

showing a cartridge chamber of somewhat different proportions serving as a means for pressing back the firing-pin after use.

The numeral 1 designates a base or frame formed in such manner as to be applicable 60 to a surface at a door or window, and having screw-holes 2 for securing it. Carried by the frame are a cartridge-chamber adapted to receive an ordinary spring-actuated firing-means, and an interference element adapted to offer yielding interference 65 to the opening of the door or window and thereby release the firing-means. There is also an adjustment whereby the device is movable into and out of interfering position. The precise form and construction 70 may be considerably varied, and I do not necessarily limit myself to the embodiment shown, though for practical purposes I deem this preferable.

Proceeding now with a description of the preferred form, it will be seen (Fig. 9) that the base is provided with one member 3 of a swivel joint 4, the axis of which is perpendicular to the base. A complementary member 5 of this joint is formed on the under part of a structure 6, which comprises a cylindrical firing-pin chamber 7. The forward end of this chamber is screw-threaded at 8 and carries a removable cartridge chamber 9. This chamber or member 9 comprises a forward portion 10 containing a bore 11 of the proper diameter to receive a metallic cartridge 12 and a rear portion 13 containing an enlarged counter-bore 14 screw-threaded to fit the end of the firing-pin chamber, there being between the bores 11 and 14 a shoulder 15 which affords a seat for the projecting rim 16 of the cartridge. Within the firing-pin chamber is a firing-pin 17, which is urged forward by a spring 18 interposed between the back of the firing-pin chamber and a forward collar 19 on the firing-pin.

The members of the swivel joint 4 are connected by a pivot screw 20, beneath the head of which in a chamber 21 in the bottom of the base is a spring washer 22. Shallow recesses 23 in one of the members of the joint and corresponding projections 24 on the other member having suitable sloped or rounded sides afford in connection with the washer a snap-action or impositive locking device for automatically positioning the structure 6 when it is turned relatively to 100

95

the base in definite positions approximately 90° apart.

The interfering part is preferably constituted by an arm 25, which is pivoted on a screw 26 fixed in a lug 27 on the rear end of the firing-pin chamber 7. One end 28 of this arm is normally caught behind a shoulder or head 29 on the rear end of the firing-pin, which is adapted to project outward 10 through a hole 30 in the back end of the firing-pin chamber. The portion 31 of the arm at the other side of the pivot 26 projects for a suitable distance and is formed with a longitudinal slot 32.

15 The swivel 4 constitutes a form of adjustment enabling the device to be set into interfering position or to be moved out of such position. In connection with an adjustment of this character a safety means is 20 provided for positively locking the device in position and also for locking the firing-pin in the non-interfering condition of the device. As a further safety, a means is also provided whereby the release arm 25 is also locked against releasing movement 25 when the device is in the non-interfering condition. In the illustration a split safety pin 33 having a ring handle 34 is employed. In the interfering or operative 30 condition of the parts, this pin is inserted at the side of the firing-pin chamber 7 of the swivel structure 6 into a socket 35 in the base, thus preventing the structure being turned clockwise, in Figs. 2 and 5, to 35 the non-interfering or inactive position, displacement of the structure in the opposite direction being prevented by a post 36 rising from the base at the opposite side of the structure or by any other suitable fixed 40 stop. In the non-interfering position of Figs. 1 and 10, the safety-pin is inserted through holes 37 in the firing-pin chamber directly in front of the firing-pin downward into another socket 38 in the base. In 45 this manner both the adjustment and the firing-pin are locked. In order automatically to lock the release-arm 25 when the device is turned to the non-interfering position, the post 36 is formed with shoulders 50 or a recess 39, in or adjacent which the projecting part of the arm lies in this position, so that it cannot be turned upon its pivot so as to release the firing-pin. In this position, therefore, the safety-pin 33 serves 55 both to lock the adjustment in the non-interfering position and to prevent the release-arm 25 being accidentally displaced from the restraint of the lock 39.

In the case of a door, the base is secured 60 by screws 40 passing through the screw-hole sockets 2 to the vertical face of a door-jamb 41 adjacent the free edge of the door 42 and inside the apartment. As thus positioned, the projecting portion of the arm 25 over- 65 lies the inner face of the inwardly opening

door when the device is set in protecting position. Consequently if the door is opened, the yielding interference afforded by the arm will cause the arm to turn upon its pivot 26, thereby disengaging its end 28 from the shoulder of the firing-pin, which is thereupon driven forward by the spring 18 against the cartridge, which is exploded, thereby giving the alarm. During the daytime, or when the protection is not desired, the device is shifted to the position of Fig. 1, in which position the interference is removed from the door, which can now be opened and closed freely without actuating the device.

80 In the case of a window, the base is attached to the top surface of the lower sash 43, in such position that when it is in the interfering condition of Fig. 4 the arm 25 overlaps one of the stiles of the upper sash 44. In this stile a suitable pin 45 is driven, so as to project within the slot 32 of the arm. Preferably there will be a series of these pins 45 at different heights, so that the window can be protected in any one of a number of open positions as well as when fully closed. In the non-interfering position the arm 25 is carried clear of the upper sash, as seen in Fig. 3.

Fig. 12 illustrates the combination of the 95 alarm device with a fume or gas producer 46, adapted to repulse or incapacitate the intruder. This means may be considerably varied and may be either mounted upon the support alongside the alarm or incorporated 100 upon the same base. A simple construction is shown, comprising a cup 47 containing a body of fume-producing material 48 and having a flash-tube 49, which in the operative condition is in line with and adjacent 105 the cartridge-chamber 9 and its cartridge 12, the flash-tube being so positioned as to conduct the flame from the exploded cartridge to the material 48, which is thereby ignited and caused to give off noxious fumes. The 110 material 48 may be, for example, a cake of sulfur, but I do not limit myself to the particular substance. As indicated at 50 a special ignition substance may be provided as a surface layer upon the cake or otherwise. A perforated cover 51 on the cup 47 may be provided to protect the contents and to guard against possible damage from escape of particles of the burning material.

The cup 47 is also connected with the base 120 52 by a swivel 53 similar to the swivel of the alarm proper, enabling it to be turned into and out of operative position.

I recognize that the form and details of the invention may be varied, and therefore 125 do not wish to limit myself to the precise construction which is herein illustrated as a preferred embodiment.

Fig. 14 illustrates a cartridge chamber member 9^a the forward portion or barrel 130

10 of which is of sufficiently narrow diameter and sufficiently long to be reversed and inserted in the firing-pin chamber to press back the firing-pin against the action of its spring, so that the firing-pin may be caught again by the arm 25 after the device has been fired.

What I claim as new is:

1. A burglar-alarm device, comprising a base having means of attachment to a surface at a door or window, and a structure movable relatively to the base, said structure including a cartridge-chamber and spring-actuated firing-means and affording also a yielding interference to the opening of the door or window whereby the firing-means is released, said structure being movable relatively to the base so as to bring the interference into and out of interfering position, and safety pin means for locking the structure in and out of interfering position, the safety pin in the non-interfering position also blocking the firing-means.

2. In an alarm for a door or other closure, a base, a structure movably mounted on the base and including a firing-pin chamber and a cartridge-chamber, a spring-actuated firing-pin in the firing-pin chamber, a release for the firing-pin affording a yielding interference to the opening of the closure, and a safety-pin structure insertable in said movable structure and into the base to lock the structure in non-interfering position and at the same time block the firing-pin.

3. In a cartridge-alarm for a door or other closure, a base, a firing-pin chamber swiveled on the base, a spring-actuated firing-pin therein, a cartridge-chamber in line with the firing-pin chamber, and a release-arm pivotally connected with the swiveled firing-pin chamber and adapted to offer interference to the opening of the closure and to be moved into and out of interfering position by turning the swivel.

JOSEPH MENCHEN.
